UNITED STATES PATENT OFFICE.

ANDREW B. HENDRYX, OF NEW HAVEN, CONNECTICUT.

DESIGN FOR A FISHING-REEL PLATE.

SPECIFICATION forming part of Design No. 27,897, dated November 23, 1897.

Application filed October 11, 1897. Serial No. 654,890. Term of patent 14 years.

To all whom it may concern:

Be it known that I, ANDREW B. HENDRYX, of New Haven, in the county of New Haven and State of Connecticut, have invented a new Design for the End Plate of a Fishing-Reel; and I do hereby declare the following, when taken in connection with the accompanying drawings and the letters of reference marked thereon, to be a full, clear, and exact description of the same, and which said drawings constitute part of this specification, and represent, in—

Figure 1, a face view of a plate for fishing-reels embodying my design; Fig. 2, a sectional view on line *a b*.

This invention relates to a design for the end plate of a fishing-reel; and it consists in the

conformation, as hereinafter described and shown in the accompanying illustrations.

The essential feature of this design is a plate A, in which is formed a centrally-arranged bearing B and lugs C C, arranged on opposite sides of said bearing, all as shown in the accompanying illustrations.

I claim—

The design for the end plate of a fishing-reel as herein shown and described.

In testimony whereof I have signed this specification in the presence of two subscribing witnesses.

ANDREW B. HENDRYX.

Witnesses:

EDWARD N. PECK,
FERDINAND A. WAGNER.
